Primary Examiner — Richard Kearney*Assistant Examiner* — Liv C Anderson(74) *Attorney, Agent, or Firm* — Bruce P. LaBrie;
Resolution Legal Group(57) **CLAIM**

The ornamental design for a spindle light, as shown and described.

DESCRIPTION

FIG. 1 is a front elevation view of a spindle light showing our new design;

FIG. 2 is a rear elevation view thereof;

FIG. 3 is a right side view thereof;

FIG. 4 is a left side view thereof;

FIG. 5 is a bottom view thereof;

FIG. 6 is a top view thereof;

FIG. 7 is a perspective view thereof; and,

FIG. 8 is a perspective view thereof.

The structural features depicted by broken lines have been shown for the purpose of illustrating portions of the spindle light that form no part of the claimed design.

1 Claim, 3 Drawing Sheets(56)
